(57) **CLAIM**

I claim the ornamental design for a lamp having x-shaped base, as shown.

DESCRIPTION

FIG. 1 is an isometric view of the novel design for a lamp having x-shaped base.

FIG. 2 is an elevational view showing the right side thereof.

FIG. 3 is an elevational view showing the left side thereof.

FIG. 4 is an elevational view showing the front side thereof.

FIG. 5 is an elevational view showing the rear side thereof.

FIG. 6 is a plan view showing the top aspect thereof; and,

FIG. 7 is a bottom plan view thereof.

The broken lines shown are for illustrative purposes only and form no part of the claimed design.
